UNITED STATES PATENT OFFICE

2,611,651

COMBUSTION TURBINE BURNER

Hans A. Altorfer, Wauwatosa, Wis., assignor to
Allis-Chalmers Manufacturing Company, Milwaukee, Wis., a corporation of Delaware

Original application April 10, 1943, Serial No. 482,561. Divided and this application February 23, 1946, Serial No. 649,721.

11 Claims. (Cl. 299—118)

1

This invention relates generally to the combustion of fluid fuel and is directed toward and contemplates the construction of a fluid fuel burning apparatus suitable for use in combustion gas turbine and other high temperature fluid systems. And this application is a division of applicant's original application filed April 10, 1943, Serial No. 482,561, now Patent 2,411,181, issued November 19, 1946.

The primary object of this invention is to minimize the erratic operation of combustion apparatus heretofore experienced and considered as being attributable, at least in part, to variations in the rate of fuel flow caused by a relative expansion or contraction of the nozzle and body portions of the burner, and/or to a non-uniform atomization of the fuel, and/or to an incomplete mixing of the atomized fuel and combustion supporting air at a point immediately adjacent the burner nozzle.

More particularly the present invention is directed toward and has as an object the provision of a fluid fuel burner embodying parts constructed and combined to impart whirl to the fuel being delivered to the atomizing nozzle, to maintain the whirling energy of the fuel substantially constant as the rate of flow thereof is varied, and to maintain the flow of fuel to and through the atomizing orifice substantially constant at a selected rate irrespective of the relative expansion or contraction of the nozzle and body portions of the burner. In addition the fuel confining surface of the atomizing orifice is preferably shaped to effect a more uniform atomization of a whirling mass of fuel flowing therethrough.

A burner constructed in accordance with this invention may also embody parts constructed and combined in a manner considered of special importance with respect to compactness, durability and reduced manufacturing cost, and accordingly the invention consists of the various details of construction, combinations of elements and arrangements of parts as is more fully set forth in the appended claims and in the detailed description, reference being had to the accompanying drawings illustrating an embodiment of the invention and in which:

Fig. 1 is a partial longitudinal section through a combustion chamber embodying a burner and air directing parts combined in accordance with this invention;

Fig. 2 is an enlarged longitudinal section through the burner proper;

Fig. 3 is an enlarged longitudinal section of the nozzle valve carrying element;

2

Fig. 4 is a left-hand end view of the element shown in Fig. 3;

Fig. 5 is a right-hand end view of the element shown in Fig. 3;

Fig. 6 is a section taken on line VI—VI of Fig. 3;

Fig. 7 is a developed view illustrating the arrangement of tangential fuel passages shown in Figs. 3 and 4;

Fig. 8 is an enlarged longitudinal section 10 through the orifice element; and

Fig. 9 is an enlarged end view of the fuel confining surface of the nozzle orifice.

In the illustrated embodiment of the invention, the combustion apparatus comprises a cylindrical shell 1 having an air admission connection 2, a coaxial mixing chamber 3 defined by a tube 4 and by axially spaced inwardly extending annular inner and outer wall members 6 and 7, respectively, forming therebetween an annular air passage 8, guide vanes 9 disposed between and connecting the outer portions of the walls 6 and 7, and a burner 11 coaxially disposed within said mixing chamber with its nozzle portion extending through and terminating a short distance beyond the coaxial opening formed by the inner peripheral edge of inner wall 6. The tube 4 is coaxially supported within combustion chamber 1 by means of radially extending coaxing lugs or brackets 12 and 13 and bolts 14, only one set of which is shown in the interest of simplicity, and wall 6 is spaced from and secured to the rear wall 16 of combustion chamber 1 by means of brackets 17 and tap bolts 18. The burner is also removably mounted on rear wall 16 by means of a plurality of tap bolts 19. The annular outer wall 7 in addition to being connected to inner wall 6 by means of guide vanes 9 is provided adjacent its outer periphery with a coaxial collar or flange 21 telescopically engaging the adjacent end of mixing tube 4 for support thereon.

Annular wall 7 extends radially inward for a short distance and then forward in coaxial parallel relation to the tube 4, whereas wall 6 extends inwardly and forwardly toward the burner with its inner peripheral edge terminating short of and surrounding the nozzle end of the burner in passage forming relation therewith. The interior of combustion chamber 1 is provided with an inwardly extending annular air directing flange 22 positioned to divert some of the air entering through the connection 2 into the passage 8 and into the passage 23 formed between annular inner wall 6 and the rear wall 16 of combustion chamber 1 from which the air flows along the burner and through the opening 24 formed 50 between the inner peripheral edge of wall 6 and 55

the nozzle portion of burner 11. The remainder of the air entering through the connection 2 is diverted by flange 22 into and forwardly through the coaxial annular space 26 provided between shell 1 and mixing tube 4. In this connection, it should be noted (see Fig. 1) that the inner annular air diverting and directing wall 6 is shaped and arranged to form with the nozzle portion of the burner an inner annular air passage of decreasing cross sectional area in the direction of air flow therethrough to thereby surround the orifice end of the nozzle portion with a high velocity air stream. The air flowing through space 26 may be used solely as cooling air or some or all of it may be subsequently mixed with the combustion products formed in mixing chamber 3. However, this feature forms no part of the invention, and a further description in this connection is deemed unnecessary for a complete understanding of same. Annular inner wall 6 in addition to directing some of the incoming air through the opening 24 also functions to direct the air entering passage 8 forwardly in an annular stream surrounding the nozzle end of the burner.

Referring to Fig. 2, it will be seen that the burner 11 embodies coaxially united body and nozzle portions 27 and 28, respectively, surrounded by a tubular radiant heat reflecting shield 29 which may be chromium plated or otherwise treated to provide a suitable reflecting surface. Shield 29 is radially spaced from and secured to the portions 27 and 28 by means of spacing blocks 31 welded to body portion 27 and screws 32 which extend through the shield and into said blocks and by having circumferentially spaced portions 33 of its nozzle end bent inward to engage the orifice end of the nozzle portion. The remaining coaxially extending nozzle end portions 34 of shield 29 support an annular member 36 in surrounding passage forming relation to the orifice end of nozzle portion 28 and in axially spaced relation to the inner peripheral edge of annular wall 6. The outside diameter of member 36 is approximately equal to the diameter of the inner peripheral edge of wall 6 and is secured to shield portions 34 in any suitable manner such as by welding. Member 36 is positioned and shaped to divert and direct the air flowing through the opening 24 provided between the inner peripheral edge of wall 6 and shield 29 and to divert and direct the inner portion of the forwardly directed annular air stream issuing from passage 8, inwardly against the fuel spray emitted from the nozzle orifice at a point immediately adjacent thereto.

Body portion 27 comprises a mounting block 37 having a bore 38 extending coaxially therethrough which has counterbored or otherwise enlarged outer and inner ends 39 and 41, respectively, and an enlarged intermediate portion 42. A first tubular member 43 is coaxially seated in counterbore 41 and forms a continuation of bore 38 and is welded or otherwise permanently secured to the block 37. A second tubular member 44 is provided with a peripheral flange 46 intermediate its ends which abuts against and is welded to the inner end of tubular member 43. The outer end portion of member 44 is telescoped within the inner end of member 43 and its inner end portion is externally threaded. And a series of bores 47 extend coaxially therethrough about the central passage 48 therein; the bores 47 and passage 48 forming continuations of the central passage in tubular member 43. Block 37 also has formed therein a transverse bore 49 which

terminates in the enlarged portion 42 of bore 38 and has its outer end threaded and connected with a fuel return pipe 51, a bore 52 which extends axially outward from counter bore 41 and terminates adjacent the enlarged portion 42 of bore 38, and a transverse bore 53 which terminates in the outer end of bore 52 and has its outer end threaded and connected with a fuel supply pipe 54.

Nozzle portion 28 comprises a first tubular member 56 (see Fig. 3) having an enlarged internally threaded outer end portion provided with a peripheral end flange 57 presenting several plain sides (see Fig. 5). An intermediate portion of member 56 is also provided with a peripheral flange 58 which is similar in shape to outer end flange 57 and with a plurality of ducts 59 extending transversely therethrough (see Fig. 6). The inner end of member 56 is reduced and provided with axially spaced series of ducts 61, 62 and 63 opening tangentially into the inner end of central passage 64 which forms a continuation of the central coaxial passages provided by tubular members 44 and 43. A second tubular member 65 surrounds member 56 in generally spaced passage forming relation therewith through engagement with the flanges 57 and 58 on member 56. The passage 66 formed therebetween is in continuous communication with the coaxial bores 47 in body member 44. Member 65 has internally and externally threaded outer and inner ends and its outer end is secured to the threaded inner end of body member 44. An orifice member 67 abuts the inner end of member 56, and a tubular clamping member 68 engages and holds orifice member 67 firmly against the inner end of member 56 by having an internally threaded outer end portion secured to the threaded inner end of member 65. Consequently, member 68 is operative to secure orifice member 67 and member 56 in coaxial abutting relation with the outer end of member 56 engaging the inner end of body member 44, as shown. A set screw 69 locks member 68 in its clamping position. A coaxial valve element 71 is disposed within tubular nozzle member 56 and has an externally threaded intermediate portion 72 engaged with an internally threaded intermediate portion of member 56 to thereby render element 71 rotatably axially movable therein. Member 71 includes a central bore 73 extending coaxially from its outer end, which extends into the central passage 48 in body member 44, to a point adjacent its inner or orifice end. Member 71 also includes a plurality of bores 74 extending outwardly therethrough from the inner end portion of bore 73.

Orifice member 67 is provided with a valve seat 76 adapted to be engaged by the orifice end of valve element 71 to close the orifice 77 therein. And the adjacent cylindrical portion of element 71 is also adapted to close the axially spaced series of ducts 61, 62 and 63 in the nozzle end of tubular member 56. The inner ends of the transverse ducts 59 in tubular member 56 terminate in a coaxial enlargement 78 of the central passage 64 therein and the outer ends of the bores 74 in valve element 71 also terminate in said enlargement to thereby maintain the coaxial bore 73 in valve element 71 in continuous communication with the space or passage 66 irrespective of whether said valve element is in its closed or fully open position. The outer end of valve element 71, that is, the portion extending within the central passage 48 in body member 44, is provided with a radially extending coaxial key 79

and the actuation of said element is accomplished by means of a coaxial rod 81 which extends into bore 38 in block 37 and terminates within the enlarged portion 42 thereof. A tube 82 is secured to the inner end of rod 81 for angular movement therewith and extends coaxially through the inner portion of bore 38, through the counterbore 41, the tube member 43 and into the central passage 48 in tube member 44 with its inner end telescoping the outer end of valve element 71. The key 79 on valve element 71 being disposed within a coaxial slot 83 formed on the inner surface of tube 82 to thereby render said element axially movable relative to said tube and angularly movable therewith. The outer end of rod 81 is provided with a handle 84 for rotating same and the counterbored portion 39 of bore 38 is filled with packing 86 which is held in place by a coaxial member 87 secured to the outer face of block member 37 by means of tap bolts 88. The outer end of tube 82 is provided with ducts 89 extending transversely therethrough and placing the interior of said tube in communication with the enlarged portion 42 which in turn communicates with the fuel return pipe 51 through the bore 49. Pipe 51 is preferably provided with a suitable valve 91 as shown in Fig. 1.

With the burner parts positioned as shown in Fig. 2 and the valve 91 in the return pipe opened, fuel under pressure from a suitable source (not shown) will flow from supply pipe 54 into bore 53, through bore 52 into the annular passage 93 formed between tube 82 and the surrounding tubular body member 43, through the coaxial bores 47 in body member 44 into the passage 66 formed between nozzle elements 56 and 65, through ducts 59 in element 56, through ducts 74 in valve element 71 into the coaxial bore 73 therein, through tube 82 and ducts 89 therein into the surrounding chamber formed by enlargement 42 in block member 37, and then through bore 49 into return pipe 51. This arrangement permits fuel oil to be circulated through the burner after operation ceases in order to keep the burner cool; the rate of oil circulation being preferably controlled by the valve 91 in return pipe 51.

When it is desired to operate the burner, the handle 84 is turned in a direction to withdraw valve element 71 from its seat 76 on orifice member 67, thereby opening said orifice and, depending upon the extent of the withdrawal, one or more of the axially spaced series of ducts 61, 62 and 63 in the orifice end of valve carrying element 56; the orifice end of valve element 71 forming with the opposed surface of orifice member 67 a coaxial fuel receiving chamber of variable axial length determined by the extent to which element 71 is withdrawn from its said seat. The axially spaced series of ducts 61, 62 and 63 are arranged to be successively opened by the withdrawal of element 71 from seating engagement with orifice member 67 and to whirl fuel entering the receiving chamber about its longitudinal axis. In other words, valve element 71 is effective to increase and decrease the size of the fuel receiving chamber as the quantity of fuel entering same is increased and decreased, respectively. This feature is of particular importance as it maintains the whirling energy of the fuel in said chamber and thereby the degree of atomization substantially constant at all times without delivering to the burner fuel in excess of that required for combustion. Consequently, fuel pumping requirements are materially reduced as it is unnecessary at any time to supply an excess of fuel

to the burner nozzle even for cooling purposes since the fuel for combustion flows through an outer surrounding passage, thereby effectively cooling the burner during normal operation; it being understood that during normal operation the valve 91 in return pipe 51 is kept fully closed and that said valve is opened when combustion ceases in order to continue the cooling action for a time interval sufficient to prevent carbonization of fuel in the nozzle portion of the burner. However, if additional cooling should be desired when operating under conditions effecting extremely high temperatures, the valve 91 may be opened to permit some of the fuel to return through the inner passage as previously described.

The degree of atomization effected by passing a whirling mass of fuel through a coaxial orifice varies materially with changes in the whirling energy of the mass which in turn varies with changes in the velocity with which the fuel enters the whirling or receiving chamber. And in this connection, it has been determined that irrespective of changes in whirling energy, better atomization is effected by providing the fuel confining wall surface of the orifice with a circumferential series of axially extending serrations, such for example, as the serrations 92 shown in Fig. 9, and that when such a serrated orifice is employed in combination with a coaxial whirling or receiving chamber, the size of which is increased and decreased as the quantity of fuel entering same is increased and decreased, respectively, the results obtained are uniformly excellent for all operating conditions. In addition, the correlation of these two features with the primary air directing means comprising annular wall 6 and annular member 36 increases both the rapidity and the extent to which the primary air mixes with the atomized fuel issuing from the nozzle orifice and thereby effects complete combustion of the resulting mixture in a space or combustion chamber of short length in the direction of gas flow therethrough. However, the primary air directing means improves the operating characteristics of any type of atomizing burner, and its use is not in any manner limited to the particular type of burner herein shown and described.

The feature of mounting the valve element 71 in and for axial movement relative to a member fixed in the nozzle portion of the burner for movement therewith is also of particular importance as it prevents an appreciable movement of the nozzle portion relative to the valve element and thereby a variation in the rate of fuel feed and/or orifice opening which always occurs when the nozzle valve is carried by a relatively cool body portion of the burner.

The invention is applicable to fluid fuel burners generally, and although a particular application has been illustrated and described in detail, it should be understood that it is not desired to limit the invention to the exact details of construction herein shown and described, as various modifications within the scope of the appended claims may occur to persons skilled in the art.

It is claimed and desired to secure by Letters Patent:

1. In a fluid fuel burner, a nozzle structure comprising means defining an elongated chamber having a plurality of axially displaced fuel admission openings directed in whirling relation with respect to the longitudinal axis of the chamber and a coaxial spray emitting orifice, said orifice having a fuel confining wall surface provided with a circumferential series of axially extending ser-

rations; an orifice and admission opening controlling valve element extending within said chamber and carried by said nozzle structure for movement therewith and for rotational longitudinal movement relative thereto, a valve actuator longitudinally fixed and rotatably mounted in a part of said burner remote from said nozzle portion, and means connecting said valve element and actuator for relative longitudinal movement.

2. In a fluid fuel burner having aligned body and nozzle parts, means within said body part including a rotatably mounted longitudinally fixed tube defining inner and outer coaxial passages, a member fixedly disposed within and carried by said nozzle part for movement therewith, means including said member defining a first coaxial nozzle passage which forms a continuation of said inner passage and terminates in a spray emitting orifice and a second nozzle passage which forms a continuation of said outer passage and communicates with said first passage through axially spaced ducts disposed adjacent said orifice, a valve element mounted within and carried by said member for movement therewith and for duct and orifice controlling movements relative thereto, said element being connected with the adjacent end of said tube to rotate therewith and to move axially relative to both said tube and member for sequentially opening said orifice and said ducts and for forming between said orifice and the orifice end of said element a coaxial chamber of variable length determined by the distance the element is withdrawn from said orifice, means including a bore in said element placing said inner passage in communication with said outer passage and with a suitable source of fuel, and means exterior of said body portion for imparting rotary movement to said tube.

3. In a fluid fuel burner, means defining an inner passage terminating in a spray emitting orifice and an outer passage surrounding said inner passage, a valve element disposed within and closing the orifice end of said inner passage and said orifice, said valve element being mounted for sufficient axial movement to open said orifice and form between said orifice and the orifice end of said element a coaxial fuel receiving chamber of variable axial length determined by the extent to which said element is withdrawn from said orifice, means for axially moving said valve element, ducts for placing said chamber in communication with said outer passage and arranged to be successively opened by the withdrawal of said element from said orifice and to whirl the fuel entering said chamber about its longitudinal axis, and means including an additional duct and a bore in said valve element placing said inner passage in continuous communication with said outer passage.

4. In a fluid fuel burner, means defining an inner passage terminating in a spray emitting orifice and an outer passage surrounding said inner passage, a valve element disposed within and closing the orifice end of said inner passage and said orifice, said valve element being mounted for sufficient axial movement to open said orifice and form between said orifice and the orifice end of said element a coaxial fuel receiving chamber of variable axial length determined by the extent to which said element is withdrawn from said orifice, means for axially moving said valve element, and ducts for placing said chamber in communication with said outer passage and arranged to be successively opened by the with- 75

drawal of said element from said orifice and to whirl the fuel entering said chamber about its longitudinal axis.

5. In a fluid fuel burner, means defining an inner passage terminating in a spray emitting orifice and an outer passage surrounding said inner passage, a valve element disposed within and closing the orifice end of said inner passage and said orifice, said valve element being mounted for sufficient axial movement to open said orifice and form between said orifice and the orifice end of said element a coaxial fuel receiving chamber of variable axial length determined by the extent to which said element is withdrawn from said orifice, means for axially moving said valve element, ducts arranged to be successively opened by the withdrawal of said element from said orifice to place said chamber in communication with said outer passage, and means including an additional duct and a bore in said element placing said inner passage in continuous communication with said outer passage.

6. In a fluid fuel burner, means defining a first fuel conducting passage terminating in a spray emitting orifice having its fuel confining surface provided with circumferential series of axially extending serrations and a second passage connected with a fuel supply pipe, a valve element disposed within and closing the orifice end of said first passage, said valve element being mounted for sufficient axial movement to open said orifice and form between said orifice and the orifice end of said element a coaxial fuel receiving chamber of variable axial length determined by the extent to which said element is withdrawn from said orifice, means for axially moving said valve element, and ducts arranged to be successively opened by the withdrawal of said element from said orifice to place said chamber in communication with said second passage.

7. In a fluid fuel burner, means defining a first fuel conducting passage terminating in a spray emitting orifice and a second fuel conducting passage communicating with said first passage through axially spaced ducts formed adjacent said orifice, a valve element disposed within and closing the orifice end of said first passage, said valve element being mounted for sufficient axial movement to close said orifice and the duct nearest said orifice, means for axially moving said valve element, and means including a bore in said element placing said first passage in continuous communication with the duct farthest from said orifice.

8. In a fluid fuel burner having aligned body and nozzle portions, means within said body portion defining inner and outer passages, valve means disposed within and carried by said nozzle portion for movement therewith, said valve means including a fixed member defining a first passage which forms a continuation of said inner passage and terminates in a spray emitting orifice and a second passage which forms a continuation of said outer passage and communicates with said inner passage through axially spaced ducts formed adjacent said orifice, said valve means including a valve element carried by said fixed member for movement therewith and for sufficient movement relative thereto to control said orifice and the duct nearest said orifice, means for effecting duct and orifice controlling movements of said valve element, and means including a bore in said element placing said first passage in continuous communication with the duct farthest from said orifice.

9. In a fluid fuel burner having alined body and nozzle portions: means within said body portion defining inner and outer passages; valve means disposed within and carried by said nozzle portion for movement therewith, said valve means including a fixed member defining a first passage which forms a continuation of said inner passage and terminates in a spray emitting orifice, a second passage which forms a continuation of said outer passage and communicates with said inner passage at a point adjacent said orifice, and an axially movable element mounted within said fixed member by mounting means that afford simultaneous movement of said valve element and said fixed member as the latter expands and contracts in response to changes in temperature, said mounting means affording selective axial adjustment of said element relative to said fixed member.

10. In a fluid fuel burner having alined body and nozzle portions, means within said body portion defining inner and outer passages, a member fixedly disposed within and carried by said nozzle portion for movement therewith, means including said member defining a first passage which forms a continuation of said inner passage and terminates in a spray emitting orifice and a second passage which forms a continuation of said outer passage and communicates with said inner passage at a point adjacent said orifice, a valve element mounted within said fixed member in threaded engagement therewith to afford simultaneous movement of said valve element and said fixed member as the latter expands and contracts in response to changes in temperature, said element being rotatably adjustable to predetermined axial positions relative to said fixed member, a valve actuator including a coaxial part projecting exteriorly of and carried by said body portion for movement relative thereto, and means connecting said valve element and said coaxial part for relative axial movement.

11. In a fluid fuel burner having alined body

and nozzle portions: means within said body portion defining inner and outer passages; valve means disposed within and carried by said nozzle portion for movement therewith, said valve means including a fixed member defining a first passage which forms a continuation of said inner passage and terminates in a spray emitting orifice, a second passage which forms a continuation of said outer passage and communicates with said inner passage at a point adjacent said orifice, and an axially movable valve element mounted within said fixed member in threaded engagement therewith to afford simultaneous movement of said valve element and said fixed member as the latter expands and contracts in response to changes in temperature, said element being rotatably adjustable in predetermined axial position relative to said fixed member.
